ALFRED E. BOARDMAN, OF SEATTLE, WASHINGTON.

AUTOMATIC SPRINKLER.

1,312,515.

Specification of Letters Patent. Patented Aug. 12, 1919.

Application filed May 28, 1917. Serial No. 171,379.

To all whom it may concern:

Be it known that I, ALFRED E. BOARDMAN, a citizen of the United States, residing at Seattle, in the county of King and State of Washington, have invented certain new and useful Improvements in Automatic Sprinklers, of which the following is a specification.

This invention relates to improvements in automatic sprinklers and, more particularly, to the nozzle valve and to devices for releasably retaining the same on its seat.

The invention has for its main object to simplify and perfect the construction and operation of devices of this character to render them more reliable and quick in action.

Another object is to provide two-part valve holding struts which will effectually withstand bending or other strains to which they are subjected and be readily separable when the fusible connections thereof become fused.

Another object is to provide means to prevent the accidental dislodgment of the struts.

Another object is the provision of a structure constituted of the valve and the retaining struts therefor subjected to strains which, upon becoming unbalanced through the agency of heat, serve to disrupt such structure and positively dislodge the valve from its seat.

An additional object is to provide a novel form of valve which will accommodate itself to various lengths of struts.

With these ends in view, and others, as will appear in the following description, the invention consists in the various novel features of construction and combination of parts, as will be hereinafter described and claimed.

In the accompanying drawings illustrating one embodiment of the invention—

Figure 1 is a side elevation of my improved automatic sprinkler. Fig. 2 is a transverse vertical section of the same. Fig. 3 is a front elevation, partly in transverse section, to illustrate the co-operative action of the parts when released and falling apart.

Figs. 4 and 5 are perspective views of complementary strut members shown detached.

The sprinkler may, as regards the nozzle 6, the boss 7, frame arms 8 and distributor 9, be of any usual or suitable construction, it

being preferable, however, to position the distributor within the frame. The boss 7 is internally screw-threaded to engage the thrust screw 10 which, in the present invention, is provided at its end with an axially disposed protruding stud 11.

12 represents a disk of suitable non-corrosive material interposed between the nozzle orifice and a valve 13 which is substantially of the form of a segment of a hollow sphere, said valve being employed with its concave side contacting with the periphery of said disk.

The valve is held in place by means of two struts arranged in the form of an inverted letter V, with their lower ends engaging 70 against stops 14 afforded by grooves provided in the valve at a greater distance apart than the external diameter of the nozzle while the upper ends of the struts bear against each other and the thrust screw 10 75 at opposite sides of the stud 11; to accommodate the latter the struts are provided with notches 5.

As illustrated, each of said struts comprises two members 15 and 16 of which the former is straight, or nearly so, and is provided near one end with an aperture 15¹. The other member, 16, is formed with a straight portion intermediate a hooked upper extremity 16¹ and a rectangularly directed element 16² which terminates in a pointed extremity 16³ in offset relation to the straight central portion of the respective member. The element 16² affords a shoulder upon which the lower end of the member 15 90 is positively supported when in operative position.

The hooked extremity 16¹ of member 16 is arranged to extend through the aforesaid aperture 15¹ to receive a globule 17 of solder 95 or other suitable fusible substance between the hook and the opposing surface, as at 15², of the member 15. By thus coupling the complementary members of a strut, the solder is subjected to compressive and not tensile strains and is directly exposed from both sides to the action of heat.

In practice, the struts are arranged to occupy the positions in which they are represented in Figs. 1 and 2; that is to say, with the upper ends of the struts bearing against each other and also against the thrust screw, and their lower ends engaging the respective

valve stops 14 which, as above mentioned, are located outside of the periphery of the nozzle.

The thrust screw is then regulated to exert 5 compressive forces through both of the diverging struts, thereby subjecting the triangularly arranged organization—constituted of the struts and valve—to strains which normally are distributed by the two struts 10 to maintain the valve on its seat and in opposition to any fluid pressure obtaining within the supply pipe.

When exposed to heat sufficient to fuse the solder of either one of the struts, the strain 15 acting thereon causes the members thereof to fall apart, as shown at the right hand side of Fig. 3, to release the adjacent side of the valve, whereupon the strain acting through the remaining strut by being applied at an 20 angle to the axis of the sprinkler and against the part of the valve which, so to speak, overhangs the nozzle, will cause the valve to be shifted laterally and tilted up for the escape of water from the supply pipe. Such 25 disengagement of the valve is consequently accomplished by the unbalanced force applied through one strut subsequent to the destruction of the other one and is not dependent upon the fluid pressure obtaining 30 within the supply pipe, as is the case with other automatic sprinkler valves known to me.

The advantages of my invention reside, principally, in the use of devices which insure 35 certainty and despatch in action. The shape of the valve enables it to seat in any position which it assumes in locating itself to suit the relative lengths of struts. The stud 11 is of importance, inasmuch as it enables 40 the thrust screw to be rotated without disturbing the two struts and also serves, after one strut has been ejected, to prevent the other one from dropping out until it has exercised a tilting action upon the valve.

45 While I have illustrated my invention as utilizing a pair of struts, each formed of separable members, it is apparent that one of the struts may, if desired, be made integral.

Furthermore, the coupling of the members 50 of a strut by a small body or globule of fusible material interposed between one of the members and the extremity of the other one may be supplemented by having the contacting surfaces soldered or "sweated" together.

55 The invention is of simple and inexpensive construction and is of symmetrical and attractive appearance.

What I claim, is—

1. In an automatic sprinkler, the combination of a nozzle, a thrust screw, a valve 60 having a concave seating face for said nozzle, and struts extending in angular relations between said screw and detachably engaging the valve at a distance apart greater than 65 the external diameter of the valve seat, one

of said struts being formed of two members separably connected by a fusible element.

2. In an automatic sprinkler, the combination of a nozzle, a thrust screw, a valve for said nozzle, and struts extending in angular 70 relations between said screw and detachably engaging the valve at a distance apart greater than the external diameter of the valve seat, one of said struts being formed of two members separably connected by a 75 fusible element.

3. An automatic sprinkler having a frame including a nozzle and an internally threaded boss, a thrust screw engaging in said boss, a valve of a substantially spherical segmental form for said nozzle, said valve being provided with spaced stops disposed at a distance apart greater than the external diameter of the valve seat, and a pair of fusible valve-retaining struts each of said 80 struts comprising two members which are respectively coupled by fusible elements, said struts being arranged to respectively engage by their opposite ends said valve stops and the thrust screw.

4. An automatic sprinkler having a frame including a nozzle and an internally threaded boss, a thrust screw engaging in said boss, a stud projecting from said screw, a valve for said nozzle, said valve being provided 95 with spaced stops disposed at a distance apart greater than the external diameter of the valve seat, and a pair of fusible valve-retaining struts, each of said struts comprising two members which are respectively coupled by fusible elements, said struts being arranged to respectively engage by their opposite ends said valve stops and the thrust screw at opposite sides of said stud.

5. An automatic sprinkler having a frame 105 including a nozzle and an internally threaded boss, a thrust screw engaging in said boss, a stud projecting from said screw, a valve of a substantially spherical segmental form for said nozzle, said valve being provided with spaced stops disposed at a distance apart greater than the external diameter of the valve seat, and a pair of fusible valve-retaining struts each of said struts 110 comprising two members which are respectively coupled by fusible elements, said struts being arranged to respectively engage by their opposite ends said valve stops and the thrust screw at opposite sides of said stud.

6. A fusible valve-retaining strut for automatic sprinklers, consisting of an apertured member, a second member formed to provide a seat for the end of the first-named member, said second named member being provided with an end adapted to extend 125 through the aperture of the other member, and a body of fusible material interposed between the referred-to member-end and the other member in proximity to the aperture thereof.

7. In combination with a valve for an automatic sprinkler, of a strut comprising a member having an aperture intermediate its length, a second member having at one end 5 a pointed extremity engageable with the valve and having adjacent thereto a shoulder to support the other member, the other extremity of the second-named strut being arranged to extend through said aperture, and a fusible element interposed between the 10 last-named extremity and the first-named member.

Signed at Seattle, Washington, this 23rd day of May 1917.

ALFRED E. BOARDMAN.
